UNITED STATES PATENT OFFICE.

LLOYD C. NICHOLSON, OF EDEN, NEW YORK.

ELECTRIC SWITCHING APPARATUS.

Application filed September 19, 1921. Serial No. 501,737.

To all whom it may concern:

Be it known that I, LLOYD C. NICHOLSON, a citizen of the United States, and a resident of Eden, in the county of Erie and State 5 of New York, have invented certain new and useful Improvements in Electric Switching Apparatus, of which the following is a specification.

My invention relates to improvements in 10 electric switching apparatus and is particularly adapted to the openings of alternating current high tension circuits such as those on which a voltage of 10,000 volts or over exists, although it may be used to advantage on lower voltage circuits carrying 15 heavy currents. One object of the invention is to provide a switch which is extremely quick in action. When used to its fullest extent the invention will provide for the operation of the circuit breaker in less than one-twenty-fifth of a second, when a short 20 circuit occurs on the line, so that the short circuit may be eliminated without disturbing the operation of rotating synchronous 25 machinery on the connected system.

My present invention is in some respects an improvement upon that described in my Patent No. 1,402,310, for electric switching apparatus, issued Jan. 3, 1922. The said 30 patent covers a construction in which the use of oil in which a circuit breaks is avoided whereby the possibility of the production of explosive vapors is done away with. In the invention covered by the said patent, as well 35 as in the present invention a pair of switch contacts are caused to separate when the circuit is to be opened, these contacts by their separation causing current to flow through a vaporizable liquid so that the liquid is 40 immediately vaporized with the result that the pressure exerted by the vapors produced causes a rapid further separation of the contacts.

An object of my present invention is to 45 produce an extremely effective and comparatively simple device of the character indicated. Further objects consist in the provision of improved details of construction and combinations of parts, all of which 50 will more clearly appear from the detailed description given below taken in connection

with the accompanying drawings which form a part of this specification.

In the drawings, Fig. 1 represents a side elevation of an apparatus embodying one 55 form of my invention;

Figs. 2 and 3 are vertical sections taken respectively on lines 2—2, and 3—3 of Fig. 1;

Fig. 4 is an end elevation of the apparatus 60 viewed in the direction of the arrows 4—4;

Fig. 5 is a vertical section taken on line 5—5 of Fig. 3 on an enlarged scale;

Fig. 6 represents a detail of construction 65 shown on an enlarged scale;

Fig. 7 is a partial side elevation of a switch arm with connected parts;

Figs. 8, 9 and 10 are respectively side elevations of a piston rod and upper and lower 70 members of the piston, disassembled;

Fig. 11 is a plan view of the lower piston member;

Fig. 12 is a side elevation of the contact member carried by the lower end of the piston rod;

Fig. 13 is an end elevation of the switch arm shown in Fig. 7 with the contact carried thereby; and

Fig. 14 is an end elevation of a portion 80 of the apparatus utilized in a multipole switch embodying a modified form of my invention, certain parts being shown in section.

Referring to the drawings, the switch, in 85 the embodiment shown in Fig. 1 is preferably formed of two units of which the one shown at the right contains what I term the "gun" in which the contact is broken in a vaporizable liquid as previously referred 90 to, together with mechanism for causing the operation of the gun and other parts while the unit at the left carries a switch blade and a stopping dash-pot and switch closing mechanism.

The unit shown at the right comprises a 95 pair of channel irons 58 supported upon insulators 55, these insulators having metal caps 70 cemented thereto with transversely extending channel irons 63, 64, secured 100 thereon and supporting the channels 58. The lefthand unit is shown as having a

frame work formed of a pair of channels 57, which are supported by transverse channels 53, 54, carried by metal caps 70 which are cemented on suitable insulators 55, the insulators of both the left and right hand units being shown as supported upon a suitable supporting frame 59.

Referring to the righthand unit, a casting 16 is shown as mounted upon the channels 58. What I term the "gun barrel" of the switch is mounted on this casting.

As shown, what I term the "gun barrel" takes the form of a cylinder 1 formed of a suitable insulating material such as fabric 15 impregnated with a phenolic condensation product, this material being of high mechanical strength, water proof and a good insulator. As shown in Fig. 5, the cylinder 1 is mounted in and supported by a short 20 cylindrical member 8 screw-threaded on a portion of its periphery and screwed into position within a cylindrical member 9, the internal diameter of which is greater than that of the cylinder 1. Member 9 is formed 25 with a bottom closure member 9¹ which may be bolted or otherwise secured on the casting 16.

The contact members which are to be separated when the circuit is to be broken 30 are mounted within the cylinder or gun barrel 1. A piston head 4 is mounted on the stem 7 which extends out of the upper end of the cylinder 1, the contact member 5 being screwed on the lower end of stem 7. The lower contact is provided by the upper end 35 of rod 6 which extends up through a suitable stuffing box 11 in the bottom portion 9¹ of the cylindrical member 9, the upper end of rod 6 and the bottom of contact member 5 normally being pressed together to form a good electrical contact. A chamber 9^a is provided by cylindrical member 9 into which water or other vaporizable liquid may be supplied, the liquid extending up into the 40 interior of cylinder 1 to a point above the plane in which the contact members 5 and 6 engage. When contact members 5 and 6 are separated from each other the water within the cylinder 1 immediately acts as a 45 conductor between said switch contact members and the current flowing through the water causes it to be rapidly vaporized to steam, and the pressure of the steam causes the piston 4 and associated parts operating 50 in cylinder 1 of the gun to be shot out of the gun with great force and rapidity.

The operating solenoid 23 is mounted on the transversely extending channel 64, between the two channels 58. The core 22 of 55 solenoid 23 is connected by a link 20 to a bell crank 24 which is pivoted on pin 10 supported by brackets 10¹ extending upwardly from the cylinder member 9 of the gun barrel construction. A spiral spring 67 is coiled about an extension of pin 10, as

shown in Fig. 3, this spring being arranged to tend to hold core 22 and connected parts in the position shown in Fig. 5 and to return the same to such position after the core has been lowered. To produce this result 70 one end of the spring may be secured to bracket 10¹ and the other end of the spring may be suitably secured to bell crank 24, or to pin 10, the bell crank being keyed to this pin. 75

The switch arm 2, as shown in Fig. 1, is pivoted adjacent to one end as shown at 40, to the brackets 42 of the unit shown at the left. Switch arm 2, which may take the form of an I beam, as shown, has the piston 80 stem 7 secured thereto adjacent its opposite end. As shown (Figs. 5 and 8) the piston stem 7 may have a pair of upwardly extending lugs 7¹ which are secured to the switch arm 2 by a pin 7^a, it being understood that current is adapted to flow from switch arm 2 through lugs 7¹, or, if desired, by a flexible connection from arm 2, to the piston stem 7 and thence to the switch contact 5 and rod 6 in contact therewith. 85

Switch arm 2 likewise carries an auxiliary contact 17 which preferably takes the form of spring fingers brazed to switch arm 2, as shown in Fig. 13. Two switch blades 19 are pivotally mounted at their lower ends on 90 pin 10 and have contacts at their upper ends adapted to engage between the contacts 17. A stirrup 21 is secured to switch blades 19 and is provided at its outer end with a cross member 21^a. A path for current from switch 100 blade 2 is provided by contacts 17 and 19 in parallel with the path provided by the piston stem 7 contact 5 and rod 6, it being noted that the external switch blade 19 may parallel the entire length of the gun barrel 1. The switch blades 19 and 17 are provided to carry the load current in excess of that which the contacts 5, 6, would carry. 105

When core 22 moves downwardly by reason of excess current flowing through 110 solenoid 23, as will be described hereafter, the lefthand member 18 of bell crank 24, (Fig. 5) moves some distance to the right, referring to Fig. 5, and then strikes a sharp blow against the cross piece 21^a of stirrup 115 21 so as to sharply disengage switch blades 19 from contacts 17 and break the circuit extending through members 17 and 19 at this point. A link 25 is pivotally secured at its upper end to a lug formed on bell 120 crank 24, the lower end of link 25 being connected by a pin and slot connection with a lever 15 which is pivotally mounted at one end to the casting 16. The rod 6 extends downwardly through the stuffing box 11 at 125 the bottom of cylinder member 9 of the gun barrel into a cylinder 14, which is supported beneath the bottom member 9¹ of cylinder 9 by any suitable means such as the supporting bolts 14¹. A piston 12 is provided 130

within cylinder 14 at the lower end of rod 6, a rod 13 extending downwardly from piston 12 and out through an opening in the bottom of cylinder 14.

5 Lever 15 carries at its free end a collar 15¹ slidably mounted on rod 6 immediately above piston 12, lever 15 operating through a suitable slot in cylinder 14. When solenoid 23 is actuated to draw down core 22, 10 the slot in link 25 permits a certain amount of movement of this link without affecting lever 15, until after the arm 18 of bell crank 24 has struck a hammer blow against cross piece 21^a of stirrup 21 to break the contact 15 between switch members 17 and 19 as described. Thereafter the upper end of the slot in link 25 strikes against the pin 25¹, which is secured to lever 15 and is slidably mounted in the slot. This results in rod 6 20 being pushed down a short distance to separate contact 5 from the upper end of the rod.

The separation of contacts 5 and 6 as stated, above causes the immediate vaporization 25 of the liquid in the gun barrel, as stated, and the pressure of the steam or gas formed, pressing upwardly on piston 4 forces the piston rapidly out of the gun barrel. Rod 6 is also rapidly pushed downwards by the 30 pressure of steam or gas on its upper end, to the end of its stroke. It will be noted that the function of lever 15 and collar 15¹ is merely to start the motion of rod 6 away from contact 5, the motion of rod 6 being 35 completed by the steam or gas pressure.

The lower end of rod 13 which extends out of cylinder 14 is secured to a link 30, the other end of which is pivotally secured to a bracket 32 extending downwardly from 40 channel 64. A spring 31 is connected at one end to the channel 63 of the frame of the apparatus the other end of the spring being connected to an arm 30¹ which forms an extension of link 30 or is secured thereto to 45 move therewith. Accordingly spring 31 will act to restore rod 6 and associated parts, after the operation of the switch, at which time the spring 67 on pin 10 will return the core 22, bell crank 24, and associated parts to their 50 normal positions. The piston 12 fits closely within cylinder 14, the cylinder acting as a dash-pot to dampen and absorb the kinetic energy of rod 6 and connected parts during the operation of the switch. A rubber 55 bumper 27 is shown as mounted on casting 16 to be contacted against by bell crank 24 on the downward movement of core 22 to stop the moving parts without injury.

The tension on spring 67 may be adjusted 60 to prevent the normal load current through solenoid 23 from operating the switch, this spring being overcome when a current in excess of the current for which the spring is adjusted comes over the line.

65 The apparatus may be designed to pro-

vide for a still larger load current in which case latching means are provided to prevent any movement of the core 22 and associated parts until a current greater than that for which the latch operating device is set comes 70 over the line. Such a construction is shown in the drawings in which, referring to Figs. 1, 3 and 5, it will be noted that link 25 is provided adjacent its upper end with a lug 25^a under which the upper end of a lever 26 75 normally engages so as to prevent any downward movement of link 25. Lever 26 is pivoted at 26¹ to the casting 16 and is provided with an outwardly extending tail piece 26^a (Fig. 3). A solenoid 28 is mounted on 80 the casting 16 beneath tail piece 26^a and is provided with a core 28¹ which is drawn upwardly into the solenoid when the latter is energized, the upper end of this core then pressing against the under side of tail piece 26^a to push the upper end of lever 26 out from under lug 25^a so as to unlatch the core 22 of solenoid 23 and the connected parts. Solenoid 28, if used, is connected in series 85 with solenoid 23. Solenoid 28 is relatively 90 small and is capable of adjustment for practically any current so that it may be adjusted to cause the operating mechanism to be unlatched whenever a current greater than a desired load current is encountered. 95

The water reservoir, or broadly speaking the reservoir for the vaporizable liquid which is to be used in the gun barrel, is shown at 35, referring to Figs. 1 and 4, and supported by uprights 38, from the 100 frame members 63 and 58. This reservoir is shown as being provided with a glass water gauge 36. The reservoir is connected by pipe 34 with the chamber within the cylindrical member 9 of the gun barrel. No 105 mechanism is required for regulating the liquid level in the reservoir since the switch operates satisfactorily with a large variation of water level.

Switch blade 2, as stated above, is pivoted 110 at 40 to the brackets 42, the switch blade being keyed to the rotatable pin or shaft 40. The brackets 42 extend upwardly from the top of a dash-pot cylinder 45, which is mounted on the frame members 57 of the 115 lefthand unit as shown in Fig. 1. Brackets 42 are provided with guideways 61, as shown in Fig. 2, in which a cross head 66 is slidably mounted. A piston rod 43 is secured near its upper end to cross head 66 and extends 120 downwardly through a suitable gland in the cover of cylinder 45. A piston 44 is mounted on the lower end of rod 43, within cylinder 45, which latter is adapted to contain oil or other suitable liquid.

The top of the rod 43 is connected to switch blade 2 in such a manner that arm 2 will be permitted a considerable pivotal movement, upon the breaking of circuit between contacts 5 and 6 in the gun barrel, 125 130

before the dash-pot piston 44 is brought into motion. In the preferred form of apparatus this connection is made by means of a bent link 39 which is pivotally connected at one end to the upper end of piston rod 43, referring to Fig. 6. The other end of link 39 is pivotally connected to switch blade 2 at a point comparatively close to pivot 40. As shown in the drawings the switch blade 2 may be provided with a saddle 41 to which the end of link 39 may be pivoted.

In the operation of this mechanism the link 39 exerts a cam like action on piston rod 43. When contacts 5 and 6 separate in the gun barrel the piston rod 7 and piston 4 will move entirely out of the gun barrel 1 before the dash-pot piston 44 is brought into motion. The dash-pot, piston rod and cross head, which are comparatively heavy, are then given a gradual acceleration, because of the cam like action of link 39 on piston rod 43. The dash-pot cylinder 45 is shown as bored with different diameters at different points along its length, so as to secure approximately uniform pressure of the oil against piston 44 by varying the clearance between the piston and the walls of the cylinder in proportion to the speed of the piston.

Preferably the piston 4 within the gun barrel 1 is so formed as to provide a sort of safety valve so that in case of opening a circuit carrying a very large current the excessive sudden steam pressure within the gun barrel will be relieved.

In the preferred form of construction, as indicated in Figs. 7 to 12 inclusive, the piston comprises an upper part 4 having an upwardly extending sleeve portion 4¹ which is adapted to be slipped over the portion 7^a of reduced diameter of the piston rod 7. A lower piston member 4^a is then positioned beneath piston member 4 and the contact terminal 5 screwed into position below that, on the screw-threaded reduced diameter portion 7^b of piston rod 7. The spring 3 coiled around the piston rod above piston member 4, serves to press the latter tightly against the lower piston member 4^a. The lower piston member is provided with radial slots 4^b and the upper piston member 4 is provided with corresponding tongues which are adapted to fit over the slots 4^b. The piston member 4^a is also preferably provided with a pair of openings 4^c therethrough and the upper piston member 4 is provided with a pair of guide pins 4^d which are adapted to seat in openings 4^c, so as to align the tongues extending around member 4 directly over the slots 4^b. With this arrangement the piston parts 4 and 4^a ordinarily work as a unit and prevent the escape of steam past the same, spring 3 being quite strong. If, however, steam of excessive pressure is suddenly generated in the gun

barrel, the piston member 4 will be raised somewhat against the action of spring 3 so as to permit the escape of some steam through the slots 4^b and so out to the atmosphere.

The upper end of the cylinder or gun barrel 1 is preferably made conical or funnel shape, as is indicated at 1¹ to facilitate the piston entering the same on the return of the parts after the actuation of the switch. It will be noted that the piston 4, 4^a, is not rigidly connected to the piston stem and is arranged to have a slight swinging motion about its axis when it enters the gun barrel, to permit it entering the same without rubbing the inside surface of the barrel.

A pair of levers 46 are fulcrumed intermediate their lengths at the upper ends of a pair of standards 47 which are in turn pivoted at their lower ends to casting 49 which is secured across the top of frame members 57. Levers 46 are pivotally connected at their righthand ends, referring to Fig. 1, to the upper end of the dash-pot piston 43. At the left hand end of levers 46 the latter are pivotally connected to a pair of vertical members 48, the lower ends of which are attached to a casting 48¹ secured on top of the insulator 50 which latter has a pin 52 of magnetic material extending downwardly therefrom within a direct current solenoid 51.

When the switch is in its open position, in which the switch blade 2 is thrown upwardly, as shown in Fig. 6, the pin 52, constituting the core of solenoid 51, is up and will, of course, be drawn down into solenoid 51 when the latter is energized so as to pull down the lefthand end of levers 46 and raise the righthand end of the same which results in swinging switch blade 2 about its pivot 40 back into position to close the switch, the piston 7 entering the gun barrel until contact 5 engages firmly against the upper end of rod 6. The solenoid 51 is aided in this movement by spring 65 which, as shown in Fig. 2, is wound about pivot pin 40 and is so connected to pin 40 and to the switch blade 2 as to tend to press the switch blade into its closed position, shown in Fig. 1. Solenoid 51 may be energized by manual control, or automatically.

The operation of the parts has been made clear to a considerable extent in connection with the preceding description. When the normal load current is flowing, the line current flows from the terminal 71 on bracket 42, shown in Fig. 2, through a flexible connection to shaft 40 and thence through the switch blade 2. The current flows in one path from switch blade 2 through piston rod 7, contact 5, rods 6 and 13, link 30 to the frame members 32, 58 and 64, and thence through solenoid 23, one terminal of which is connected to a frame member 58, to the

other terminal of the solenoid 23, indicated at 23¹, this forming a terminal of the apparatus. Current also flows, in shunt to the path described, from switch blade 2 through contacts 17 and 19 to the frame work of the machine and thence through solenoid 23 to the terminal 23¹. When the latch operating solenoid 28 is used the latter may be connected in series in the path just described 10 as by connecting the same between the solenoid 23 and the frame member 58.

When an undesirable overload occurs on the line, as for example a short circuit due to an insulator failure or an arc on the line, 15 the increase in current in solenoid 23 causes it to pull down its core and open the switch 17, 19, whereupon all of the current is caused to flow through the shunt path through contact members 5 and 6. As the core 22 de-scends further collar 15¹ on lever 15 depresses rod 6 so that the upper end of rod 6 is separated from contact 5. The current flowing across the gap between members 5 and 6 rapidly vaporizes the water within 25 the gun barrel to form steam and the steam pressure immediately forces piston 4 and associated parts rapidly out of the gun barrel and forces rod 6 downwardly, rapidly and completely breaking the line circuit. 30 Any arc tending to form between contacts 5 and 6 is extinguished or prevented from forming due to the high pressure of the steam. Furthermore the fact that the contacts are separated with great speed and in 35 the presence of water or in a semi-conducting medium tends to prevent the formation of an arc. The switch blade 2 swings upward rapidly without retardation until after the piston 7 has been thrown entirely 40 out of the gun barrel after which the cam link 39 becomes effective to depress the dash-pot piston 44 whereupon the moving parts of the dash-pot construction are gradually brought into motion, the kinetic energy of 45 switch blade 2 being thus absorbed and this member brought to rest.

Thereupon, or as soon as solenoid 51 is energized, switch blade 2 is swung back into operative position, piston 4 again entering 50 the gun barrel and contact 5 coming into engagement with the upper end of rod 6 which has been moved upwardly into operative position, as soon as the inertia of its downward movement has been overcome, by 55 spring 31, while at the same time spring 67 serves to raise core 22 and bell crank 24 into operative position, the arm 18 of bell crank 24 striking against the rear cross piece 21^b of stirrup 21 to force switch blades 19 back 60 into engagement with switch contacts 17. The apparatus operates so rapidly that the circuit is opened and the overload or short circuit switched off the line before the rotating synchronous machinery on parallel 65 connected systems will get out of step or lose

its load. On the deenergizing of solenoid 28, when the circuit is broken between contact 17 and 19 latch lever 26 swings back into position to again engage beneath lug 25^a when link 25 again rises to the position 70 shown in Fig. 5.

The same principles of operation may be carried out in connection with a multipole switch, as is indicated in Fig. 14. As many switches as desired, such for example as 75 three, may be employed, each of the same being similar to the switch mechanism which has been described. Each of these will be provided with a switch blade 2¹ pivotally mounted on a shaft 40¹, these elements corresponding to the switch blade 2 and the shaft 40 previously described. As is shown in Fig. 14 shafts 40¹ are extended towards each other in alignment and are connected together by suitable insulators 70. As is indicated in Fig. 14, shafts 40¹ may be provided with springs 65¹ corresponding to the spring 65 previously described, and all of the other parts of each switch apparatus 80 may be the same as those already described. 85

With such an arrangement the switch blades 2¹ of a multipole circuit breaker will all move together to make and break the various circuits controlled thereby. Such an apparatus may be used, for example, in 90 controlling a three phase system. In such a system the original short circuit may, of course, be only in two phases leaving the third phase unopened and still in circuit. In such a case when an apparatus such as 95 is indicated in Fig. 14 is used having three switch elements with three blades 2¹ mechanically connected together, the opening of the circuit in two phases would, of course, serve to open the third phase at the same 100 time.

In connection with the apparatus which has been described above it may be noted 105 that the mechanical construction whereby the movement of the piston 7 out of the gun barrel is permitted to take place without retardation, the movement of the switch blade 2 carrying the piston 7 being thereafter gradually brought to rest with a 110 gradual acceleration of the moving parts of the dash-pot, has been found particularly effective. In this mechanism a rapidly moving body, namely the switch blade 2, is pivoted near one end and is brought to rest 115 by connecting the comparatively heavy parts of the stopping mechanism to the swinging switch blade near its pivot point where its motion is comparatively slow.

It will also be noted that the present construction provides an arrangement whereby 120 separation between the contacts 5 and 6 is caused to take place rapidly by causing the rod 6 to move downwardly through a considerable distance, comparatively speaking, 125 while the upper contact has only to move up- 130

wardly through a comparatively short distance until it is clear of the gun barrel. This arrangement permits the piston to extend into the gun barrel only a comparatively short distance when it is in its operative position. It will also be noted that the auxiliary contact blade 19 extends in parallel with the gun barrel substantially throughout the entire length of the latter. 10 It will also be noted that the construction is comparatively simple as to all its parts and is positive in its operation.

It will be understood that many changes and modifications may be made without departing from the spirit and scope of the invention, the invention not being limited to the details shown and described, the scope of the invention being indicated by the appended claims.

20 What I claim is:—

1. In switching apparatus, the combination of a cylinder open at one end, a piston therein having its stem extending from said cylinder, a contact carried by said piston, a second contact normally in engagement with said first contact, a pivoted arm outside said cylinder having the upper end of said piston stem connected thereto and carried thereby, said contacts being included in an electric circuit, said piston being adapted to be moved rapidly out of said cylinder upon separation of said contacts, a dash-pot having a piston, and means for operatively connecting said dash-pot piston to said pivoted arm adjacent to its point of pivotal support.

2. In switching apparatus, the combination of a cylinder, open at one end, a piston therein having its stem extending from said cylinder, a contact carried by said piston, a second contact normally in engagement with said first contact, a pivoted arm outside said cylinder having the upper end of said piston stem connected thereto and carried thereby, said contacts being included in an electric circuit, said piston being adapted to be moved rapidly out of said cylinder upon separation of said contacts, a dash-pot having a piston, and means positioned to be actuated by a point on said pivoted arm near the pivot thereof to actuate said dash-pot piston.

3. In switching apparatus, the combination of a cylinder open at one end, a piston therein having its stem extending from said cylinder, a contact carried by said piston, a second contact normally in engagement with said first contact, a pivoted arm outside said cylinder having the upper end of said piston stem connected thereto and carried thereby, said contacts being included in an electric circuit, said piston being adapted to be moved rapidly out of said cylinder upon separation of said contacts, a dash-pot having a piston, and means positioned to be actuated by said pivoted arm to actuate said

dash-pot piston only after said first named piston has moved out of said cylinder.

4. In switching apparatus, the combination of a cylinder open at one end, a piston therein having its stem extending from said cylinder, a contact carried by said piston, a second contact normally in engagement with said first contact, a pivoted arm outside said cylinder having the upper end of said piston stem connected thereto and carried thereby, said contacts being included in an electric circuit, said piston being adapted to be moved rapidly out of said cylinder upon separation of said contacts, a dash-pot having a piston, and a cam link connecting said dash-pot piston with a point on said pivoted arm adjacent the pivot thereof whereby pressure will be exerted on said dash-pot piston in gradually increasing amount to actuate the same and thereby stop the movement of said pivoted arm.

5. In switching apparatus, the combination of a cylinder open at one end, a piston therein having its stem extending from said cylinder, a contact carried by said piston, a second contact normally in engagement therewith, a pivoted arm outside said cylinder having the upper end of said piston stem connected thereto and carried thereby, said contacts being included in an electric circuit, said piston being adapted to be moved rapidly out of said cylinder upon separation of said contacts, an auxiliary switch member carried by said arm, a movable switch member adapted to engage therewith, said switch members being included in a circuit, in shunt with said first and second contacts, and means for moving said movable switch member out of engagement with said auxiliary switch member.

6. In switching apparatus, the combination of a cylinder open at one end, a piston therein having its stem extending from said cylinder, a contact carried by said piston, a second contact normally in engagement therewith, a pivoted arm outside said cylinder having the upper end of said piston stem connected thereto and carried thereby, said contacts and arm being included in an electric circuit, said piston being adapted to be moved rapidly out of said cylinder upon separation of said contacts, an auxiliary switch member carried by said arm, and a movable switch member adapted to engage therewith and to extend parallel to the entire length of said cylinder, said switch members being included in a circuit in shunt with said first and second contacts.

7. In switching apparatus, the combination of cooperating switch contact members, a piston connected to operate one of said members, a cylinder in which said piston and said members operate, a solenoid, a switch outside said cylinder in shunt relation to said contact members comprising a

- pivoted contact arm and a contact engaged thereby, means for maintaining a vaporizable liquid about said first mentioned contact members, a bell crank connected to the 65
 5 core of said solenoid and adapted to strike a blow upon said pivoted arm to open the switch, upon movement of said core, and means for thereafter, during movement of said core, separating said first mentioned 70
 10 contact members.
8. In switching apparatus, the combination of cooperating switch contact members, a piston connected to operate one of said members, a cylinder in which said piston 75
 15 and said members operate, a solenoid, a switch outside said cylinder in shunt relation to said contact members comprising a pivoted contact arm having a cross piece secured thereto and a contact engaged by said
 20 arm, means for maintaining a vaporizable liquid about said first mentioned contact members, a lever connected to the core of said solenoid adapted upon movement of said core to move a distance and then strike
 25 said cross piece to disengage said pivoted arm from the contact engaged thereby, and means for thereafter, during movement of said core, separating said first mentioned 80
 30 contact members.
9. In switching apparatus, the combination of cooperating switch contact members, a piston connected to operate one of said members, a cylinder in which said piston 85
 35 and said members operate, a solenoid, a switch outside said cylinder in shunt relation to said contact members comprising a pivoted contact arm and a contact engaged thereby, means for maintaining a vaporizable liquid about said first mentioned contact members, a bell crank connected to the core of said solenoid and adapted to strike a blow upon said pivoted arm to open the switch upon movement of said core, and
 40 link and lever connections between said bell 90
 45 crank and the second of said first mentioned contacts to thereafter, during movement of said core, move said second contact out of engagement with the first mentioned of said contacts.
- 50 10. In switching apparatus, the combination of cooperating switch contact members, a piston connected to operate one of said members, a cylinder in which said piston 95
 55 and members operate, a dash-pot in alignment with said cylinder, a rod connecting the second of said contact members with the piston of said dash-pot, means for maintaining a vaporizable liquid about said contact members, electro-responsive means having a movable element, a lever extending into said dash pot and engaging the piston thereof, and connections between the movable element of said electroresponsive means 100

- and said lever for moving the second of said contact members out of engagement with the first upon movement of said movable element.
11. In switching apparatus, the combination of cooperating switch contact members, a piston connected to operate one of said members, a cylinder in which said piston and members operate, a dashpot in alignment with said cylinder, a rod connecting the second of said contact members with the piston of said dash-pot, means for maintaining a vaporizable liquid about said contact members, electroresponsive means adapted when the current therethrough exceeds a predetermined value, to separate said contact members, said parts being arranged to then permit a comparatively long movement of said rod and second contact member, and a shorter movement of said piston and first contact member within said cylinder under the pressure of the vapor generated upon the separation of said contacts.
12. In switching apparatus, the combination of cooperating switch contact members, a piston connected to operate one of said members, a cylinder in which said piston and said members operate, a solenoid, a switch outside said cylinder in shunt relation to said contact members comprising a pivoted contact arm and a contact engaged thereby, a connection between the core of said solenoid and said pivoted contact arm for disengaging the latter from its cooperating contact after said core has moved an appreciable distance, upon flow of excess current through said solenoid, and means, including a lost motion connection, for causing movement of said first mentioned connection to separate said first mentioned contacts after movement of said pivoted contact arm.
13. In switching apparatus, the combination of cooperating switch contact members, a piston connected to operate one of said members, a cylinder in which said piston and said members operate, a solenoid having a core, means operated by movement of said core for controlling the movement of the other of said contact members, latch means for preventing movement of said core, electroresponsive means in circuit with said solenoid adapted to trip said latch means when a current greater than a predetermined value flows therethrough, and means for maintaining a vaporizable liquid about said first mentioned contact members.
- Signed at Buffalo in the county of Erie and State of New York, this 15th day of Sept. A. D. 1921.

LLOYD C. NICHOLSON.
